(57) **CLAIM**

The ornamental design for a sling bag as shown and described.

DESCRIPTION

FIG. 1 is a front, left and top perspective view of a sling bag showing my new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof; and,

FIG. 8 is a rear, left and bottom perspective view thereof. The broken lines in the figures illustrate portions of the sling bag that form no part of the claimed design.

1 Claim, 8 Drawing Sheets
